UNITED STATES PATENT OFFICE.

WILLIAM F. BOCKHOFF, OF RICHMOND, INDIANA, ASSIGNOR TO THE NATIONAL AUTOMATIC TOOL COMPANY, OF RICHMOND, INDIANA, A CORPORATION OF INDIANA.

UNIVERSAL JOINT.

Application filed March 25, 1920. Serial No. 368,525.

To all whom it may concern:

Be it known that I, WILLIAM F. BOCKHOFF, a citizen of the United States, residing at Richmond, in the county of Wayne 5 and State of Indiana, have invented certain new and useful Improvements in Universal Joints, of which the following is a specification.

My invention relates more especially to 10 universal joints through which power is transmitted, as for example in the case of multiple drill spindles. The object is to provide a simple and strong joint whose parts are few in number and of no such unusual 15 character or form as to require any special or exceptional treatment in their production. All the individual parts are of rather conventional type and can be economically and expeditiously turned out in quantity- 20 production by ordinary machine-shop practice. The parts are adapted to be assembled with the utmost dispatch and when assembled not only supply a joint of great strength and power-transmitting capacity, 25 but one which is proof against derangement under any of the great variety of conditions in use.

In the drawings which accompany and form part of this specification, Fig. 1 represents the joint in elevation; Fig. 2 shows it 30 in longitudinal section, and Fig. 3 in cross-section.

The numeral 2 designates the usual tubular heads which are pinned to the shafts, 35 and each formed with a pair of arms or jaws 3. The numeral 4 designates a coupling member in the form of a substantially solid cube which is straddled two ways by the said arms or jaws. The latter are bored and 40 countersunk to receive headed studs 5 and the cube is bored in like diameter for the passage of these studs to its hollow center from the four directions. The block or cube is bored in fairly large diameter from end to 45 end and the four studs project to an appreciable extent inwardly beyond the interior cylindrical wall of the cube, their inner ends being beveled on opposite sides as most clearly shown in Fig. 3, so that they nest together at the center of the block. These 50 inwardly projecting ends of the studs are diametrically drilled to provide through-openings, the outermost parts of which will come substantially flush with the interior wall of

the block. Plain pins 6 are received in these 55 openings through the studs, being of a length to extend an appreciable distance beyond each side of the same. These pins lie snugly against the inner wall of the block and hold the studs in securely with their 60 heads seating in the countersinks of the openings in the arms or jaws of the tubular heads. It is not absolutely essential that the studs have heads; they might be perfectly plain, in which case there would be 65 no countersinking in the arms or jaws and inward movement of the studs would be limited by their contact with each other where their beveled inner surfaces meet together. At the same time there is a decided advantage 70 in using headed studs particularly in cases where the outside diameter of the forked heads is required to be kept down to small dimensions. Thus the heads of the studs serve to resist spreading of the arms 75 of the forked heads and a lighter cross section of arms will serve. Of course this anti-spreading function of the headed studs is dependent upon adequate securing of the studs against outward movement, which is 80 accomplished by the cross pins 6.

In the interior cylindrical wall of the block at a corresponding distance from each end there is formed an encircling groove 7, the distance between the two grooves being 85 equal to the length of one of the stud-retaining pins 6. Each of these grooves is adapted to be occupied by a spring ring 8 of split character for contraction in being forced into the end of the main bore of the block 90 and then expansion into the groove. The depth of the latter is about half the diameter of the wire out of which the spring ring is made so that the latter may obtain a secure seat while at the same time projecting 95 amply over the ends of the pins 6. Each spring ring is preferably formed with an inwardly turned extension 9 lying across its diameter and bent or humped for the purpose of supplying a convenient formation 100 to facilitate handling the ring both when inserting it and when occasion arises for removing it.

It will be seen that with the two spring rings in place the retaining pins which hold 105 the studs in are themselves securely guarded at both ends so that there is no chance for them to come out. It will further be ap-

parent that the objects primarily stated are thoroughly accomplished by the construction above described.

I claim:

- 5 1. A universal joint comprising forked heads, an open-center coupling block, connecting studs projecting into the center of the block, cross-pins running through projecting portions of the studs, and means for positively confining the pins.
- 10 2. A universal joint comprising forked heads, an open-center coupling block, connecting studs projecting into the center of
- the block, cross-pins running through the studs, and means engaging the ends of the 15 pins and the interior wall of the block to hold the pins in place.
3. A universal joint comprising forked heads, an open-center coupling block, grooved around its interior, connecting studs 20 projecting into the center of the block, cross-pins running through the studs, and spring rings engaging the grooves and projecting across the ends of the pins.

WILLIAM F. BOCKHOFF
